UNITED STATES PATENT OFFICE.

HERMAN C. HEFFNER, OF MARTINSBURG, WEST VIRGINIA.

INSULATOR-HOLDER.

1,095,860.

Specification of Letters Patent.

Patented May 5, 1914.

Application filed May 25, 1912. Serial No. 699,752.

To all whom it may concern:

Be it known that I, HERMAN C. HEFFNER, a citizen of the United States, residing at Martinsburg, in the county of Berkeley and State of West Virginia, have invented new and useful Improvements in Insulator-Holders, of which the following is a specification.

This invention relates to insulator supports and more particularly to that type which are adapted to support the insulator upon a cross arm.

One of the principal objects of the invention is to avoid difficulties heretofore encountered in insulator supports, that of weakening the cross arm.

With the old type of locust supporting pins, it was necessary to drill the cross arm, thus weakening the same and in order to overcome this, it was necessary to use a cross arm having a considerably larger cross sectional area.

It is the object of this invention not only to avoid this difficulty, but to permit the use of a smaller cross arm and at the same time, reinforce the same so as to prevent splitting and to assist in preventing warping of the arm.

A further object of the invention is the provision of a metallic insulator supporting device which is so constructed as to prevent breakage of the insulator by reason of the different coefficients of expansion between the metal and porcelain or glass.

A further object of the invention is the provision of a simple and efficient device of this character which will not only insure longevity of the cross arm but which will be equally as durable as the present type of insulator support and far less liable to fracture.

Further objects of this invention will appear as the following specific description is read in connection with the accompanying drawing, which forms a part of this application, and in which:

Figure 1 is a perspective view of the cross arm with the support attached thereto and with the ordinary type of petticoat insulator mounted therein. Fig. 2 is a vertical sectional view therethrough. Fig. 3 is a perspective view of the mounting device removed. Fig. 4 is a detail longitudinal sectional view through a cross tie showing the modified form of brace holder. Fig. 5 is a perspective view of the brace holder removed. Fig. 6 is a perspective view of a modified

form. Fig. 7 is an elevation thereof shown applied to a cross arm. Fig. 8 is a top plan view showing one form of coil or insulator receiving screw. Fig. 9 is a similar view of another form of insulator receiving screw. Fig. 10 is a side elevation of a wall insulator support.

Referring more particularly to the drawing, 1 represents an ordinary cross tie and 2 the ordinary type of petticoat insulator now in common use. The mounting device is constructed of a single strand of wire bent back upon itself intermediate its ends to produce a substantially rectangular loop 3 which is adapted to surround the cross tie, as shown in Figs. 1 and 2. The portions of the strand beyond the second loop are extended up substantially parallel to each other, as shown at 4, and are then bent or coiled around the portion 4 into spiral form, as shown at 5, the terminal ends of the strand being extended laterally in opposite directions, as indicated at 6 and having eyes 7 formed at their ends to receive the fastening devices 8, here shown in the form of screws.

In the modified form shown in Figs. 4 and 5, the plate 9 has formed in its ends, suitable boxes 10 to receive the terminal or looped ends of the strand which, in this instance, are sprung into the boxes, as shown. This plate is held down upon the top of the cross arm by the insulator mounting device and is prevented from longitudinal movement by oppositely projecting spurs 11 which are adapted to enter the cross-arm, as shown. When the two parts or spirals are brought together, as shown in Fig. 2, the separate coils thereof, will interlock and form a substantially rigid screw which engages the threads 12 on the interior of the insulator 2. The act of threading the insulator on to the screw will tend to draw the separate coils together and to clamp the device around the cross arm. Thus, the cross arm will be reinforced and prevented from splitting.

Referring to the modification shown in Figs. 6 and 7, the mounting device is constructed of separate strands of wires 13 and 14 pivotally connected together, as shown at 15, and each being provided with a screw coil 16 and the bracing ends 17 having eyes 18 to receive attaching devices. In this type of device, it will be readily seen how the same may be applied to the cross arm between other insulators which are already in place thereon. For instance, if it is de-

- sired to put an insulator close to the pole, it would be necessary with the structure shown in Fig. 1 to remove all insulators or to slip them up and retie the wires thereon and then place the additional insulator on the outside. With this type, the pivoted parts are so arranged that they can be readily placed around the cross arm and the coils 16 brought together to receive the insulator.
- 10 The coils may be constructed as in Fig. 8 with a flat side 19, in which case, the flat portions of opposite coils only overlap each other the width of the material of which the coils are formed, while, if the coils are made 15 in the form shown in Fig. 9, they will mesh with each other, as shown. The coil shown in Fig. 10 is constructed of a single strand of wire with loops formed intermediate its length, as shown at 20, to receive fastening 20 devices and with its opposite legs converging for a predetermined distance and then extending at an angle, as shown at 21, and arranged along parallel lines. The outer ends of the legs have the wire coiled around 25 them into insulator receiving screws 22, while the terminals of the coils have oppositely extended diagonal brace members 23 having eyes 24 for the reception of fastening devices. This type of device is here 30 shown as secured to the side of a cross arm, but it will be readily understood that it may be attached to a wall batten, to the side of a pole, or to a tree.
- What is claimed is:—
- 35 1. An insulator holder comprising separated open coils of wire arranged to inter-engage and form an insulator receiving screw and integral means for securing the coils on a support which surrounds the support and reinforces the same.
- 40 2. An insulator holder comprising separated open coils of wire arranged to inter-engage and form an insulator receiving screw of adjustable diameter.
- 45 3. An insulator holder comprising separated open coils of wire arranged to inter-engage to produce an insulator supporting screw and means for securing the coils to a support which surrounds the support and 50 reinforces the same.
4. An insulator holder comprising separated open coils of wire arranged to inter-engage to produce an insulator supporting screw and integral means connected to each coil and adapted to be drawn around a support for reinforcing the same upon application of an insulator to the coils. 55
5. An insulator holder comprising separated open coils of wire arranged to adjustably inter-engage to produce an insulator supporting screw, integral extensions formed at one terminal of the coils, said extensions having means for receiving fastening devices for connecting and holding the coils against longitudinal movement over a support and integral means connected to the opposite terminal of the coils and arranged to surround the support for securing the coils thereto and for reinforcing the support. 60
6. An insulator holder comprising a single strand of wire having a substantially complete loop formed intermediate its ends, open coils of wire formed around the terminals of the loop and integral therewith, said coils arranged to inter-engage to produce an insulator supporting screw and means to hold the coils against movement over a support. 65
7. A device of the class described comprising a single strand of wire having a substantially complete loop, the ends of which extend away from the loop and have the terminals thereof coiled therearound to form separate open spirals arranged to inter-engage to produce an insulator supporting screw, together with means to connect the coils to a support which prevents longitudinal movement of the coil over said support. 70
8. An insulator holder comprising supporting means and separate open coils of wire adjustably inter-engaged to produce an insulator supporting screw, said coils being integrally connected to the supporting means. 80
- In testimony whereof I affix my signature in presence of two witnesses.
- HERMAN C. HEFFNER.
